15 Claims. (Cl. 62—3)

1

This invention relates to mechanical refrigerating apparatus and particularly to two-temperature refrigerating machines employing secondary refrigerant systems.

In order to accommodate a sufficient amount of frozen foods many household refrigerators are now being made with two separate compartments. One of these compartments is maintained at a very low temperature, for example, 0° to 10° F., in order to provide for the storage of frozen foods and for the freezing of ice cubes. The second compartment, which is used for the storage of other types of food, is maintained at a temperature of about 35° to 40° F. To achieve the two widely separated temperatures required for the freezing compartment and for the general food storage compartment a primary refrigeration system may be provided for cooling the freezing compartment and a secondary refrigerating system for cooling the general food storage compartment. The secondary refrigerating system is dependent upon the primary system for its operation and it is necessary in order to maintain the desired temperature in the food storage compartment to provide some means of control within the secondary refrigerating system which will allow the maintenance of a higher temperature by the secondary system despite the continued operation of the primary refrigerating system at a much lower temperature. Accordingly, it is an object of this invention to provide an improved control apparatus for use with a secondary refrigerating system.

It is another object of this invention to provide improved apparatus for controlling the flow of refrigerant in a refrigerant circulating system.

Where the evaporator in a refrigerating system is not operated on a defrosting cycle it is necessary that provision be made for the removal from time to time of the frost accumulating on such evaporator. Accordingly, it is another object of this invention to provide an improved defrosting arrangement for the evaporator of a refrigerating system.

Further objects and advantages of this invention will become apparent as the following description proceeds and the features of novelty which characterize this invention will be pointed out with particularity in the claims annexed to and forming a part of this specification.

For a better understanding of this invention reference may be had to the accompanying drawings in which Fig. 1 is a side elevation, partly in section, of a household refrigerator incorporating one embodiment of this invention; Fig. 2 is an enlarged view, also partly in section, showing details of the flow controlling device which is incorporated in the refrigerator shown in Fig. 1;

2

and Fig. 3 is an illustration of a modified form of this flow controlling arrangement which incorporates apparatus for defrosting the secondary system.

Referring now to the drawings, Fig. 1 shows a household refrigerator having a thermally insulated cabinet in which are included a machinery compartment 1, a food storage compartment 2, and a freezing compartment 3. The thermal insulating material is indicated generally by 4. Access to the food storage and freezing compartments is provided by means of doors 5 and 6, respectively.

The freezing compartment 3 is refrigerated by a primary refrigerating system which includes compressing and condensing apparatus (not shown) within the machinery compartment 1, a primary evaporator 7 and a liquid receiver 8. The liquid receiver 8 includes a float valve or other suitable device (not shown) for controlling the flow of refrigerant to the primary evaporator 7. The liquid refrigerant from the condensing unit in the machinery compartment 1 is supplied to the liquid receiver through a liquid line 9 which is shown in heat exchange relation with the return suction line 10. The liquid refrigerant, under the control of the float valve, is supplied from the receiver 8 to the primary evaporator 7 through a conduit 11. The vaporized refrigerant from the primary evaporator is withdrawn from the header 12 through the suction conduit 10. As shown in Fig. 1, this suction conduit is preferably looped about the receiver 8 in heat exchange relationship to cool the noncondensable gases in the liquid receiver.

The temperature of the primary evaporator may be controlled in any suitable manner. In Fig. 1 apparatus for controlling this temperature is illustrated as including a temperature responsive bulb 13 connected in the usual manner by a tube 14 to any suitable motor control switch arranged within the housing 15.

Turning now to the secondary refrigerating system illustrated in Fig. 1, this system includes a condensing portion or condenser 16, an evaporating portion or evaporator 17 and a flow controlling apparatus, indicated generally as 18, for controlling the flow of condensed refrigerant from the condenser 16 to the secondary evaporator 17. As illustrated in Fig. 1 the condenser 16 is placed in intimate heat exchange relation with the primary evaporator 7. This may be accomplished, for example, by securing the tube comprising the condenser in intimate contact with the primary evaporator 7 by several clamps, two of which are indicated at 19 and 20 in Fig. 1. The secondary evaporator 17 is composed of several turns disposed in serpentine arrangement

about the food storage compartment 2 and secured to the exterior of the liner of this compartment to accomplish the refrigeration thereof. Although the secondary evaporator has been shown secured to the exterior of the liner of the compartment 2 in a manner well known in the art, it will be apparent that this evaporator could, if desired, be arranged within the compartment 2, just as the primary evaporator is arranged within the compartment 3. The flow controlling apparatus 18 includes a condensate flow control chamber 21, a condensate reservoir 22, a conduit 23 which connects the condensate flow control chamber with the condenser 16, a conduit 24 for transmitting liquid refrigerant from the condensate flow control chamber 21 to the secondary evaporator 17 and a conduit 25 for transmitting liquid refrigerant from the condensate flow control chamber 21 to the condensate reservoir 22. The vaporized refrigerant from the secondary evaporator 17 is returned to the condenser 16 through a conduit 26. A bellows 27, which is connected to be actuated by a thermostatic bulb 28 placed within the food storage compartment 2, is employed in connection with the condensate flow control chamber in a manner which will be described in greater detail in connection with Fig. 2. Although the bulb 28 is placed within the compartment 2 in the form illustrated, it will be apparent that it may, if desired, be placed in contact with the secondary evaporator 17 and be directly responsive to the temperature of this evaporator, in the same manner as the bulb 13 is placed in contact with the primary evaporator 7. For calibration purposes an opposing spring may be provided for the bellows in a manner well-known in the art.

Referring now to Fig. 2, the condensate flow control chamber 21 is provided with an inlet 23 for the liquid refrigerant and two outlets 24 and 25 for the liquid refrigerant, leading to the secondary evaporator 17 and the condensate reservoir 22 respectively. In order to direct the liquid refrigerant from the conduit 23 to the secondary evaporator 17 or to the condensate reservoir 22, there is provided within the condensate flow control chamber 21 a vane or member 29 which is free to pivot on a shaft 30. This member or baffle 29 is made of a magnetic material for reasons which will appear as this description proceeds. To control the position of the member 29 and hence to control the distribution of the liquid refrigerant as indicated above, a permanent magnet 31 is provided. In order that the magnet 31 may control the position of the member 29, the chamber 21 or at least the lower portion thereof between the magnet 31 and member 29 is made of a nonmagnetic material. The magnet 31 is mounted on a supporting arm or member 32, which in turn is mounted on a shaft (not shown) which is generally in line with shaft 30. The position of the member 32 and hence the position of the member 29 is controlled by the expansible bellows 27 which is connected by a link 33 to the member 32. Since the bellows 27 is mounted by a bracket 34 in fixed relationship to the condensate flow control chamber 21, the expansion and contraction of the bellows 27 in response to the thermostatic bulb 28 will result in a corresponding transmission of motion to the member 32 through the link 33. Movement of the member 32 will cause a corresponding motion of member 29 since, as stated previously, member 29 is comprised of magnetic material which will be influenced by the magnet 31. It will be apparent that

the above-described apparatus will direct the liquid refrigerant to the conduits 24 and 25 in any proportions required, as indicated by the temperature responsive bulb 28, or the flow may be cut off entirely from one or the other of the conduits 24 and 25.

In order that the condensate directed to one side or the other of the condensate flow control chamber 21 will be conducted to the proper conduit 24 or 25, there is provided barrier 35 which prevents passage of condensate from one side of the chamber 21 to the opposite side along the lower portion thereof. As can be seen by reference to Fig. 2, the top of this barrier is higher than the opening to conduits 24 and 25 and hence, the level of the condensate in the bottom of chamber 21 cannot rise above the top of the barrier. This prevents flow of condensate from one side of the barrier to the other and insures that condensate directed to one side or the other by member 29 will be conducted to the proper conduit.

In order to provide a relatively stable condition and to eliminate a frequent or continuous oscillation of the member 29, arrangement is made for continuously supplying a small amount of refrigerant to the secondary evaporator. The amount of refrigerant so supplied is in the neighborhood of ten per cent of the maximum refrigerant which could be supplied directly from the chamber 21 to the conduit 24. This amount of refrigerant will compensate to some extent for the normal heat leakage into the storage compartment 2 and hence will prevent a rapid fluctuation of temperature which otherwise would require that the member 29 frequently vary the amount of refrigerant supplied to the secondary evaporator. This continuous supply of refrigerant to the secondary evaporator 17 is provided through a restricting tube or duct 36, sometimes referred to as a "capillary tube," connected between the condensate reservoir 22 and the conduit 24. The diameter and length of this restricting tube is so chosen as to supply the desired amount of refrigerant to the conduit 24 and thence to the secondary evaporator 17, even though the main supply of refrigerant thereto has been cut off by the member 29. The condensate reservoir 22 is connected by a conduit 37 to the conduit 26 in order to conduct refrigerant vaporized in the condensate reservoir directly to the condenser 16.

The operation of the refrigerating system illustrated in Figs. 1 and 2 is as follows. Liquid refrigerant is supplied from the condensing unit in machinery compartment 1 through the receiver 8 and float valve therein to the primary evaporator 7, the flow of refrigerant to the primary evaporator 7 being controlled by the float valve located in the receiver 8. Heat is extracted from the freezing compartment resulting in a reduction in the temperature thereof. Refrigerant is supplied to the primary evaporator until the primary evaporator reaches some predetermined minimum temperature. When this minimum temperature is reached, the compressor will be stopped by operation of the motor control switch under control of thermostat 12. Conversely when a predetermined upper limit of temperature has been reached, the compressor will again be started through operation of the motor control switch.

Vaporized refrigerant in the closed secondary system is condensed in the condenser 16 as a result of the extraction of heat therefrom by

the primary evaporator 7 with which the condenser 16 is in intimate heat exchange relationship. Fig. 2 illustrates the position of the member 29 at a time when the temperature in the food storage compartment has reached its predetermined minimum, for example 35° F. Under this condition the upper end of the member 29 is positioned to the right of the conduit 23 and hence all of the liquid refrigerant from the condenser 16 is directed by the member 29 through the conduit 25 and thence into the condensate reservoir 22. A small amount of liquid refrigerant from the condensate reservoir 22 is supplied to the secondary evaporator 17 during this period through the restricting tube 36. The amount of refrigerant supplied through this restricting tube 36 is sufficient to compensate for at least a portion of the normal heat leakage into the storage compartment 2. Whenever the heat load exceeds the amount which can be carried in this manner, there will be an increase in the temperature within the storage compartment 2. As a result of this increase in temperature the thermostatic bulb 28 will cause an expansion of the bellows 27. This causes a counterclockwise movement of the member 32 and of the magnet 31. The member 29 will be moved to a position somewhat to the left of the right-hand side of the conduit 23 and will therefore cause a portion of the liquid refrigerant flowing through conduit 23 to be directed through the conduit 24 to the secondary evaporator. If the amount of liquid refrigerant so directed through the conduit 24 is not sufficient for the requirements of the food storage compartment 2 and the temperature therein continues to rise, this temperature increase will be reflected in a further expansion of the bellows 27. This additional expansion of the bellows 27 will result, in the manner previously described, in a further counterclockwise movement of the member 32 and of the member 29. This will result in a further increase in the amount of liquid refrigerant which is directed through the conduit 24, and a corresponding reduction in the amount of liquid refrigerant which is directed through the conduit 25 to the condensate reservoir 22. Any further increase in the temperature of the food storage compartment 2 will result in additional counterclockwise movement of the member 29 until, should the temperature conditions necessitate, all of the liquid refrigerant flowing through the conduit 23 may be directed to the conduit 24 and thence to the secondary evaporator 17. As the temperature of the food storage compartment 2 is reduced, the bellows 27, under the control of the thermostatic bulb 28, will begin to contract and a clockwise movement of the member 32, and a corresponding clockwise movement of the member 29, will result. As the temperature in food storage compartment 2 continues to decrease there will be a further clockwise movement of the member 29 until, should the temperature reach the predetermined minimum, all of the liquid refrigerant from the conduit 23 will be directed through conduit 25 to the condensate reservoir. Under this condition the only liquid refrigerant which will be supplied to the secondary evaporator 17 will be that flowing from the condensate reservoir through the restricting tube 36, as has been previously explained.

It is contemplated that the secondary system shown in Figs. 1 and 2 will be operated on a defrosting cycle, that is, the secondary evaporator

will operate for a sufficient portion of each refrigerating cycle over a temperature range which will be adequate to remove any frost which collects during the remainder of the cycle. Since it 5 may be desirable to operate on other than a defrosting cycle, in the modification of this invention illustrated in Fig. 3, an arrangement is provided for removing any frost which may accumulate on the secondary evaporator. Referring now 10 to Fig. 3, it will be seen that most of the elements are the same as those previously illustrated in Fig. 2. These include the thermostatic bulb 28 and bellows 27, the condensate flow control chamber 21, the condensate reservoir 22, the restricting tube 36, and the conduits 24, 25, 26 and 31. The conduit 23 is connected slightly to the left of the position shown in Fig. 2 in order that the upper end of member 29 will be just to the right of the conduit 23 when the member 29 is in the position freely assumed under the force of gravity. This is a factor in the accomplishment of the defrosting, as will be explained below. In view of the slight shifting of the position of conduit 23, the link 33 will be of different length or the position of bellows 27 will be shifted relative to that used in Fig. 2 in order to secure the same normal operation of the system. In the modification illustrated in Fig. 3 the permanent magnet 31 has been replaced by an electromagnet 38, in order that its control of the member 29 may be eliminated when necessary for defrosting. It will be recalled that in the embodiment illustrated in Fig. 2 a small amount of liquid refrigerant was supplied to the secondary evaporator through the restricting tube 36, even though the main flow of liquid refrigerant through the conduit 24 should be cut off by the member 29. In order to defrost the secondary evaporator effectively it is desirable that this flow of refrigerant through the restricting tube 36 be prevented, and this is accomplished by providing apparatus for heating the restricting tube 36. This heating causes a vaporization of refrigerant therein and thereby effectively blocks the flow of liquid refrigerant therethrough. The 45 specific apparatus for heating the restricting tube 36 illustrated in Fig. 3 is a resistance element 39. In order to control the operation of the defrosting apparatus a switch 40, having two elements 41 and 42, is provided. In the embodiment shown in 50 Fig. 3 there is illustrated the switch 40 as being operated by an automatic timing device 43, which operates the switch at any predetermined time to accomplish the defrosting. It will be apparent, however, that the switch 40 may be manually operated or may be controlled by any other suitable apparatus, for example by a device dependent on the formation of frost on the secondary evaporator 17. Power for the electromagnet 38 and for the resistance element 39 is 55 supplied from lines 44 and 45. Line 44 is connected directly to both the electromagnet 38 and the resistance element 39. Line 45 is connected to the electromagnet 38 through switch element 41, and line 45 is connected to the resistance element 39 through switch element 42. The switch members 41 and 42 are so arranged that when one element closes the circuit through its cooperating contacts the other element will simultaneously open the circuit through its cooperating contacts.

The operation of this apparatus shown in Fig. 3 during normal refrigeration is the same as that previously discussed in connection with the embodiment of my invention illustrated in Fig. 2. During normal operating of the system, the

switch 40 is positioned so that the element 41 closes the circuit to the electromagnet 38, and element 42 is spaced from its contacts so that the circuit through the resistance element 39 is open. Under these conditions the electromagnet 38 will be energized and will control the member 29 in exactly the same manner as did the permanent magnet 31 illustrated in Fig. 2.

To defrost the secondary evaporator, the switch 40 is operated to cause element 41 to open the circuit to the electromagnet 38 and to cause element 42 to close the circuit to the resistance element 39. The deenergization of the electromagnet 38 eliminates its control on the member 29, and this member assumes its gravity-influenced position in which its upper end is to the right of conduit 23, as illustrated in Fig. 3. In this position, all of the liquid refrigerant through conduit 23 is directed by the member 29 to the conduit 25 and thence to the condensate reservoir 22, and no liquid refrigerant is allowed to pass through the condensate flow control chamber 21 to the conduit 24. Because of the deenergization of electromagnet 38 it will be seen that even though the temperature in the food storage compartment 2 should rise considerably above its normal range and there should be a continued expansion of the bellows 21, there would be no alteration in the above-indicated position of member 29. At the same time the current through the resistance element 39 causes a heating of the liquid refrigerant in the restricting tube 36 and a consequent vaporization of the refrigerant. This vapor effectively blocks the flow of liquid refrigerant through the restricting tube 36, since this tube, as is well-known in the art, will pass liquid refrigerant but will be substantially blocked by gaseous refrigerant. Consequently, the supply of liquid refrigerant to the secondary evaporator is cut off and, upon the resulting rise in temperature, defrosting of this evaporator is accomplished. When it is desired to terminate the defrosting, the switch 40 is operated to close the circuit to the electromagnet 38 and simultaneously to break the circuit to the resistance element 39, and normal operation of the system is resumed.

While this invention has been described in connection with two-temperature household refrigerators employing secondary refrigerating systems, other applications will be readily apparent to those skilled in the art. Therefore, this invention is not to be limited to the particular constructions shown and described and in the appended claims, all modifications are intended to be covered within the spirit and scope of this invention.

What is claimed as new and desired to be secured by Letters Patent of the United States is:

1. Refrigerating apparatus comprising a primary evaporator, a secondary refrigerating system including an evaporating portion and a condensing portion, said condensing portion being in heat exchange relation with said primary evaporator, means providing a control chamber in said secondary refrigerating system between said condensing portion and said evaporating portion, a condensate reservoir in communication with said secondary refrigerating system, and a movable baffle in said control chamber for selectively directing condensate from said condensing portion to said evaporating portion or to said condensate reservoir.

2. Refrigerating apparatus comprising a primary evaporator, a secondary refrigerating system including an evaporating portion and a con-

densing portion, said condensing portion being in heat exchange relation with said primary evaporator, means providing a control chamber in said secondary refrigerating system between said condensing portion and said evaporating portion, a condensate reservoir in communication with said secondary refrigerating system, and a movable baffle in said control chamber for varying the amount of condensate directed to said evaporating portion and oppositely varying the amount of condensate directed to said condensate reservoir.

3. Refrigerating apparatus comprising a primary evaporator, a secondary refrigerating system including an evaporating portion and a condensing portion said condensing portion being in heat exchange relation with said primary evaporator, means providing a control chamber in said secondary refrigerating system between said condensing portion and said evaporating portion, a condensate reservoir in communication with said secondary refrigerating system, a movable baffle in said control chamber for selectively directing condensate from said condensing portion to said evaporating portion or to said condensate reservoir, and a restricting conduit for conducting condensate from said condensate reservoir directly to said evaporating portion at a predetermined limited rate.

4. Refrigerating apparatus comprising a primary evaporator, a secondary refrigerating system including an evaporating portion and a condensing portion, said condensing portion being in heat exchange relation with said primary evaporator, means providing a control chamber in said secondary refrigerating system between said condensing portion and said evaporating portion, a condensate reservoir in communication with said secondary refrigerating system, a movable baffle in said control chamber for selectively directing condensate from said condensing portion to said evaporating portion or to said condensate reservoir, and means dependent on a condition in said secondary refrigerating system for automatically controlling the position of said movable baffle.

5. Refrigerating apparatus comprising a primary evaporator, a secondary refrigerating system including an evaporating portion and a condensing portion, said condensing portion being in heat exchange relation with said primary evaporator, means providing a control chamber in said secondary refrigerating system between said condensing portion and said evaporating portion, a condensate reservoir in communication with said secondary refrigerating system, a movable baffle in said control chamber for selectively directing condensate from said condensing portion to said evaporating portion or to said condensate reservoir, and thermostatically-controlled means for automatically controlling the position of said movable baffle.

6. In a mechanical refrigerating apparatus for use with household refrigerators of the type which include a low temperature compartment and a higher temperature compartment, a primary evaporator for refrigerating the low temperature compartment, a secondary refrigerating system including an evaporating portion and a condensing portion, said evaporating portion being adapted to refrigerate the higher temperature compartment, said condensing portion being in heat exchange relation with said primary evaporator, means providing a control chamber in said secondary refrigerating system

between said condensing portion and said evaporating portion, a condensate reservoir in communication with said secondary refrigerating system, a movable baffle in said control chamber for selectively directing the condensate from said condensing portion to said evaporating portion or to said condensate reservoir, and temperature responsive means for controlling the position of said movable baffle.

7. In a mechanical refrigerating apparatus for use with household refrigerators of the type which includes a low temperature compartment and a higher temperature compartment, a primary evaporator for refrigerating the low temperature compartment, a secondary refrigerating system including an evaporating portion and a condensing portion, said evaporating portion being adapted to refrigerate the higher temperature compartment, said condensing portion in heat exchange relation with said primary evaporator, means providing a control chamber in said secondary refrigerating system between said condensing portion and said evaporating portion, a condensate reservoir in communication with said secondary refrigerating system, a movable member in said control chamber for selectively directing the condensate from said condensing portion to said evaporating portion or to said condensate reservoir, a restricting tube for conducting condensate from said condensate reservoir to said evaporating portion, and means for heating said restricting tube to prevent the flow of refrigerant therethrough.

8. In a mechanical refrigerating apparatus for use with household refrigerators of the type which includes a low temperature compartment and a higher temperature compartment, a primary evaporator for refrigerating the low temperature compartment, a secondary refrigerating system including an evaporating portion and a condensing portion, said evaporating portion being adapted to refrigerate the higher temperature compartment, said condensing portion being in heat exchange relation with said primary evaporator, means providing a control chamber in said secondary refrigerating system between said condensing portion and said evaporating portion, a condensate reservoir in communication with said secondary refrigerating system, a movable member in said control chamber for selectively directing the condensate from said condensing portion to said evaporating portion or to said condensate reservoir, an electromagnet adjacent said movable member positioned in response to the temperature of the food storage compartment for controlling the position of said movable member, a restricting tube for conducting condensate from said condensate reservoir to said evaporating portion, means for heating said restricting tube to prevent the flow of refrigerant therethrough, and means for simultaneously deenergizing said electromagnet and energizing said heating means to defrost said evaporating portion.

9. In a refrigerating system, an evaporator and a condenser in a closed refrigerating circuit, a condensate reservoir outside said circuit but in communication therewith, a duct for conveying liquid refrigerant from said condensate reservoir to said evaporator, and means for heating said duct to control the flow of liquid refrigerant therethrough.

10. In a refrigerating system, a condensing portion, an evaporating portion, means providing a control chamber between said condensing portion

and said evaporating portion, a condensate reservoir in communication with said chamber, a movable member in said chamber for directing refrigerant from said condensing portion selectively to said evaporating portion or to said condensate reservoir, a duct for conducting refrigerant from said condensate reservoir to said evaporating portion, and means for heating said duct to control the flow of refrigerant therethrough.

11. In a refrigerating system, a condensing portion, an evaporating portion, means providing a control chamber between said condensing portion and said evaporating portion, a condensate reservoir in communication with said chamber, a movable member in said control chamber for directing refrigerant from said condensing portion selectively to said evaporating portion or to said condensate reservoir, an electromagnet for controlling the position of said movable member, a duct for conducting refrigerant from said condensate reservoir to said evaporating portion, means for heating said duct to control the flow of refrigerant therethrough, and means for simultaneously deenergizing said electromagnet and energizing said heating means to defrost said evaporating portion.

12. A secondary volatile refrigerating system of the type having substantially the same pressure throughout, said system comprising, in combination, an evaporator adapted to vaporize refrigerant liquid by the absorption of heat, a vessel adapted to vaporize refrigerant liquid at a slower rate than said evaporator, a condenser adapted to condense the refrigerant vapor generated by said evaporator and said vessel, conduit means for conducting the refrigerant liquid condensed by said condenser to said evaporator, said conduit means including a vertical portion having a gap therein through which said liquid drops, and a baffle adapted for movement into and out of said gap, said baffle being formed to deflect the refrigerant liquid flowing from said condenser into said gap to said vessel when said baffle is moved into said gap.

13. The refrigerating system defined in claim 12 including a quantity of volatile liquid refrigerant in said system not in excess of the capacity of said vessel.

14. The refrigerating system defined in claim 12 including actuating means responsive to heat for effecting the movements of said baffle.

15. The refrigerating system defined in claim 12 wherein said system includes a chamber enclosing said baffle, magnetic material associated with said baffle to move the same, said magnetic material being located within said chamber, magnetic material located outside of said chamber and adapted to move the magnetic material located within said chamber, and means responsive to heat for moving the magnetic material located outside said chamber.
